United States Patent Office

Des. 189,464
Patented Dec. 20, 1960

189,464

HELICOPTER

Irven H. Culver, Burbank, and Donald E. Walters, Calabasas, Calif., assignors to Lockheed Aircraft Corporation, Burbank, Calif.

Filed Feb. 3, 1960, Ser. No. 59,251

Term of patent 14 years

(Cl. D71—1)

Fig. 2

Figure 1 is a perspective view of a helicopter embodying our new design;

Figure 2 is a front elevational view thereof;

Figure 3 is a top plan view thereof; and

Figure 4 is a side elevational view thereof.

The dominant features of our design reside in those portions shown in full lines.

We claim:

The ornamental design for a helicopter, substantially as shown and described.
